(57) **CLAIM**

The ornamental design for a glass shower panel of shower enclosure, as shown and described.

DESCRIPTION

FIG. 1 is a perspective view of the glass shower panel of shower enclosure showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of another embodiment of the glass shower panel of shower enclosure of FIG. 1;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof;

FIG. 14 is a bottom plan view thereof;

FIG. 15 is a perspective view of yet another embodiment of the glass shower panel of shower enclosure of FIG. 1;

FIG. 16 is a top plan view thereof;

FIG. 17 is a front elevation view thereof;

FIG. 18 is a left-side elevation view thereof;

FIG. 19 is a right-side elevation view thereof;

FIG. 20 is a rear elevation view thereof;

FIG. 21 is a bottom plan view thereof;

FIG. 22 is a perspective view of still another embodiment of the glass shower panel of shower enclosure of FIG. 1;

FIG. 23 is a top plan view thereof;

FIG. 24 is a front elevation view thereof;

FIG. 25 is a left-side elevation view thereof;

FIG. 26 is a right-side elevation view thereof;

FIG. 27 is a rear elevation view thereof; and,

FIG. 28 is a bottom plan view thereof.
